UNITED STATES PATENT OFFICE.

THEODORE A. BLAKE, OF NEW HAVEN, CONNECTICUT.

STONE-CRUSHER.

SPECIFICATION forming part of Letters Patent No. 308,236, dated November 18, 1884.

Application filed May 5, 1884. (No model.)

To all whom it may concern:

Be it known that I, THEODORE A. BLAKE, of New Haven, in the county of New Haven and State of Connecticut, have invented new Improvements in Stone-Crushers; and I do hereby declare the following, when taken in connection with accompanying drawings and the letters of reference marked thereon, to be a full, clear, and exact description of the same, and to which said drawings constitute part of this specification, and represent, in—

Figure 1, a top or plan view; in Fig. 2, a longitudinal section of the same; and in Figs. 3 and 4, modifications.

15 This invention relates to an improvement in that class of stone-crushers in which a series of crushing-jaws are arranged, and which are now known as "multiple-jaw crushers."

In a patent granted to me April 15, 1884, 20 No. 296,914, I show an improvement in this class of stone-crushers. A series of jaws is arranged, all of which are movable toward and from each other, and so that the movement of one jaw communicates movement to the next 25 jaw through the material introduced between them, and all the jaws, in crushing, move in the same direction.

The object of my present invention is the construction of a crusher composed of a series 30 of jaws in which the alternate jaws are independent of the intermediate jaws, whereby the crushing action of the several jaws of the series is not dependent upon the material being crushed; and the invention consists in two series of jaws, the jaws of one series alternating 35 with those of the other series, the movement of one series being independent of the other series, as more fully hereinafter described.

A, B, C, and D represent the jaws of one series. These are connected as in a frame, as 40 seen in Fig. 1, so that all are firmly united and immovable as to each other. The adjacent faces of these jaws are inclined upward and away from each other, so as to form a mouth wider at the top than at the bottom. E, F, and G are intermediate jaws, of like 45 shape with the jaws B C—that is, double-faced—and in like manner inclined. These jaws are constructed or applied to a frame, H, 50 so as to stand intermediate between the jaws A B C D, as seen in Fig. 2. The face of one

jaw of one series and the face of the next jaw of the other series form a convergent mouth, substantially the same as in the well-known Blake crusher. Now, if a reciprocating movement be imparted to one of the series, that movement in one direction will crush against one face of the intermediate jaws, so that, of the material introduced between these jaws, the portion in one mouth will be crushed in 60 one direction of movement, and that in the next mouth will be crushed in the movement in the opposite direction. As here represented, I make the first series, A B C D, stationary, and the frame H, carrying the series E F G, movable. To this movable series I impart reciprocating movement—say by a toggle, I, at one end, and a toggle, J, at the other end—operated by eccentrics on the driving-shafts in the usual manner of communicating reciprocating 70 movement to stone-crusher jaws. The one toggle closing as the other opens, and vice versa, will give a forced movement to the series E F G, first in one direction and then in the opposite direction, and so that of the material introduced into the mouths between the jaws of the series the portion in the mouths *a b c* will be crushed as the jaws E F G move in one direction, and then on the return the material in the mouths *e f g* will be in like manner 80 crushed, the material crushed passing down, as in the Blake crusher.

Instead of making one of the series stationary and the other movable, both may be made movable, as seen in Fig. 3, a toggle being applied alike at each end of both series; and these may be operated from a single eccentric at the respective ends of the machine, as seen in that figure, the movements of the two being in opposite directions.

Instead of making the two series in a direct line, as thus far described, they may be in a circle, as seen in Fig. 4, the series being composed, say, of two plates or frames, one carrying the jaws A B C, &c., the other the intermediate jaws, E F G, &c., one of the series being stationary and the other movable, or both made movable. This movement may be made as represented in Fig. 4, the two plates or frames being arranged concentric with each other, and so as to turn upon a center or bearing, *h*, an arm, L, extending from one plate,

and an arm, M, from the other plate, with a toggle, J, between, and upon the opposite side like arms L M, with a toggle, I, between. The one toggle opening as the other closes will im-
5 part an oscillatory movement to each plate, or, if one be stationary, will impart an os-
cillatory movement to the other plate, pro-
ducing the same reciprocating crushing move-
ment between the faces of the jaws as in the
10 first illustration.

By making the two series of jaws independ-
ent of each other, and also independent of the
material between them as to crushing move-
ment, the crushing will be performed in each
15 mouth regardless of the others, and if per-
chance there be no material in one mouth, the
crushing will go on the same in the others.

I claim—

In a multiple-jaw stone-crusher, the combi-
nation of one series of jaws, A B C, &c., a sec-
ond series of jaws, E F G, alternating with the
said series A B C, the jaws of each series be-
ing connected and independent of the other
series as to movement, and mechanism, sub-
stantially such as described, to impart recip-
rocating movement, whereby all the jaws of
one series receive a crushing movement to-
ward the jaws of the other series, substantially
as described. 20 25
